UNITED STATES PATENT OFFICE

LIMA R. LEWIS, OF PHILADELPHIA, PENNSYLVANIA

PROTECTING HOOD FOR SWITCH TERMINALS

Application filed January 4, 1930. Serial No. 418,633.

The present invention relates to improvements in electric switches and, particularly, refers to means for protecting the switch terminals of electric switches for outdoor use on electrical power transmission lines and the like.

The principal object of the invention is to provide means for shielding the fixed contacts of the switch which cooperate with the movable switch blade so as to prevent the accumulation of ice, snow and other foreign substances thereon and, consequently, interference with the operation of the switch, such means entirely enclosing said contacts when the switch is not in circuit-closing position.

Another object of the invention is to provide a hood or housing by which the above-mentioned parts are shielded and which comprises a fixed and a movable section, the movable section giving ready access to the interior when the switch blade is actuated to make contact with said parts.

A further object of the invention is to provide a housing for such parts adapted to be opened by the movable switch blade when the latter is operated to close the circuit and also when the switch blade is disengaged from the switch contact and at other times to form a hood which completely guards the contacts against exposure to the weather.

Other objects and advantages of the invention will appear more fully hereinafter from the following detailed description taken together with the accompanying drawings, in which:

Fig. 1 is a plan view of a hood for a switch on a high-voltage line made in accordance with my invention;

Fig. 2 is a front elevation thereof;

Fig. 3 is a left end elevation;

Fig. 4 is a sectional view taken on the line 4-4 of Fig. 2, showing the switch blade in the act of opening the hood; and

Fig. 5 is a view similar to Fig. 4 with the end of the switch blade in its final engaging position and the hood closed.

Referring to the drawings, numeral 1 indicates the base of the switch structure. On the base is a fixed section 2 of a hood and a movable section 3 of the same into which

the fixed section 2 telescopes to some extent at the top and ends when the hood is completely closed. The two sections 2 and 3 have the form shown and the movable section 3 swings on a pivot rod 4 mounted in perforated lugs or bearings 5 attached to the base

1. Normally, the sections 2 and 3 are held in closed position with the edges of the section 3 overlapping those of section 2 by a spring 6 inside the hood which extends between the sections and is secured to each of the sections so that it normally tends to draw them together. Within the hood are fixed contact members 7 which are adapted to be engaged by a movable switch member 8. The member 8 may be of considerable length and the end remote from that, which enters the hood and engages the contact members 7, may be pivoted (not shown) so that the member may be swung up and down on the pivot as an axis. When this movable member is dropped, the end thereof pushes the section 3 away from the section 2 against the tension of the spring 6 and is inserted between the two contact members 7 to make contact therewith, as indicated in Figs. 4 and 5.

The edge of one end of the section 2 comprises a shoulder 9 positioned above the base 1, and from the shoulder the edge is substantially vertical to the top, as indicated at 10 in the present instance. The edges of the section 3 are vertical at both ends, as indicated at 11 but bent out at 12 so that the top of section 3 is extended to overlap the top of the section 2 when the parts are in the position shown in Figs. 1, 2, 3 and 5. The lower portion 11 of the edge of one end of the section 3 is spaced some distance from the edge 10 of the adjacent end of the section 2 when the hood is closed so as to leave an elongated vertical aperture 13 in one end of the hood of approximately the same area as the cross-section of the end of the switch blade 8. When the switch blade 8 projects into the hood, it will fill approximately the whole area of the aperture 13. The opposite end of the hood is not provided with an aperture because the edge of the section 2 has no shoulder, as shown in broken lines in Fig. 2. The section 2 carries at one end thereof a fixed

element or projection 14 which extends upwardly to cooperate with a similar projection or element 15 on the section 3. The projection 14 is bent to extend out at its upper end from the hood so that the two elements 14 and 15 are not in the same plane but may overlap to some extent when the hood is closed, as indicated in Figs. 2, 3 and 5. The adjacent edges of the projections 14 and 15 are diagonally inclined at the top. Thus, when the switch blade 8 is operated on its pivot and lowered to engage the contact members 7, it first engages the inclined edges 16 and 17 of the projections 14 and 15 and forces these projections and, consequently, the sections 2 and 3 apart, as shown in Fig. 4, against the tension of the spring 6. As the end of the blade 8 drops into the hood, it engages the contact members 7 and the spring 6 draws the sections 2 and 3 together again to close the hood. Inside the hood is a closure member 18 in the form of a rectangular plate in the present instance suspended from one end to swing freely on a pivot 19 on the inner surface of the end of the section 3 to close the aperture 13 when the movable switch blade 8 is out of engagement with the contact members 7 and when the sections 2 and 3 are in closed relation. Therefore, even when the switch is not in the circuit-closing position, the aperture 13 is closed and no sleet or snow or ice can penetrate the hood and lodge upon the contact members 7.

Within the hood, the base 1 carries a pair of perforated lugs 20 to receive bolts 21 on which are mounted a pair of resilient arms 22 which are perforated to receive a bolt 23 having a head and nuts to prevent these arms from moving away from each other except to the required extent. The bolt 23 is above the bolts 21 and the nuts on the bolts 23 may be set as required to adjust the tension of the resilient arms 22 against the members 7. The contact members 7 are positioned between these arms and are perforated at their lower ends so that the bolt 23 may pass therethrough. Each of the members 7 has a boss 24 thereon with a reduced projection 25 adapted to pass through openings in the upper ends of the resilient arms 22. Thus, when the end of the switch blade 8 drops between the members 7, the members can separate to some extent, the arms 22 then yielding to allow the members 7 to move away from each other, the lower ends thereof sliding on the bolt 23. This arrangement provides an efficient electrical contact between the switch blade 8 and the fixed contact members 7 and is claimed in a co-pending application of William R. Huttinger, Serial No. 340,280, filed August 11, 1928.

The base 1 may be provided with a terminal-receiving socket 26 to receive a conductor 27. The ends of the rod 4 may be perforated to receive cotter pins 28 to hold the rod in

place. Screws 29 are provided to hold the fixed section 2 rigidly upon the base 1. This type of hood is intended for high-voltage switches for outdoor use in localities where cold and inclement weather prevails during certain seasons of the year and the hood, as described, will effectively protect the contact members 7 against clogging by ice, etc., because it shields the members against the effects of exposure to the atmosphere by completely enclosing the parts in question even shutting the aperture 13 by means of the swinging closing plate 18 on the inside of the hood.

The operation of the structure may be summarized as follows:—When the switch is to be closed, the switch blade 8 is lowered about its pivot (not shown) until the end, shown on the drawing, comes in contact with the edges 16 and 17 of the projections 14 and 15. A further downward movement of the switch blade forces the movable section 3 away from the section 2 so that the blade may pass therebetween to engage the contact members 7, forcing these away from each other because of their sliding engagement at their lower ends on the bolt 23 and because of the yielding of the upper ends of the resilient arms 22 which maintain the members 7 in efficient contact with the blade 8. When the switch blade comes to rest on the shoulder 9, it fills the aperture 13 and the spring 6 pulls the sections 2 and 3 together. When the switch blade 8 is in the circuit-closing position, the closure member 18 cannot return to its vertical position but will rest in an inclined position against the upper edge of the blade 8, as shown in Fig. 5. When the circuit is to be opened, the switch blade 8 is raised and strikes against an inclined edge 12a of the projection 15 adjacent the edge 12 of the section 3. The section 3 is thus again forced away from the section 2 and after the blade 8 has cleared the projections 14 and 15, the spring 6 pulls back the section 3 and makes it overlap to some extent the section 2 so that the closure member 18 may then swing into vertical position to close the aperture 13. The edge 12a preferably overlaps the edge 12 so that contact is made between this edge and the blade 8 when the blade is lifted, thus avoiding wear on the section 3 of the hood.

Thus, it will be seen that the construction of the hood, though quite simple, is made very effective to shield the contact members 7. The switch blade 8 can easily engage the fixed contact member 7 and be disengaged therefrom. The hood is closed at all times whether the blade 8 is up or down. Any snow or ice which may collect on the outside of the hood will be dislodged for the most part by the blade 8 in its movements into or out of the hood between the projections 14 and 15 and thus, the switch can be maintained in good operating condition at all times.

Although, I have shown only one embodiment of my invention for the purposes of illustration and description, other modifications and changes may be apparent to those skilled in the art without departing from the scope of the invention and I, therefore, desire to be limited only by the scope of the appended claims.

I claim:

10 1. A protective hood for an electric switch comprising sections mounted to be relatively movable by one of the elements of said switch to give access to other elements of said switch, said sections being formed to provide an 15 aperture through which said first-named element is adapted to extend, and means adapted to close said aperture when said element is disengaged from said other elements and withdrawn from said hood, thereby affording 20 a complete enclosure for said other elements.

2. A protecting hood for electric switches, comprising relatively movable sections, one of which telescopes within the other, switch 25 contacts within said hood, said sections overlapping each other and forming at one end an aperture therethrough for a switch blade to project into said hood and engage said contacts, and a pivoted closure member adapted 30 to close said aperture when the switch blade is disengaged from said contacts and withdrawn from said hood thereby affording a complete enclosure for said contacts.

3. A protective hood for enclosing switch 35 contacts, comprising a fixed section and a pivotally-mounted movable section to engage said fixed section in telescopic relation, said sections overlapping each other to form at one end an aperture therethrough for a switch 40 blade to project into said hood and engage said contacts, and a pivoted closure member co-acting with said movable section to close said aperture when the switch blade is disengaged from said contacts and withdrawn 45 from said hood thereby affording a complete enclosure for said contacts.

4. A hood for enclosing switch contacts, comprising a base, a fixed section on said base having a horizontal shoulder in the edge of 50 one end thereof, a movable section on said base within which the fixed section telescopes, the ends of the movable section having edges with diagonal upper portions extending outward, a projection on said end of the fixed 55 section and extending upward with an edge inclined away from the movable section, a projection on the movable section and extending upward with a diagonal edge overlapping the diagonal edge of one end of the movable 60 section and having a diagonal edge extending in the reverse direction, the last-named diagonal edge intersecting with the diagonal edge of the first-mentioned projection, whereby they are forced apart to open the hood 65 when the movable switch blade is inserted

between said projections, switch contacts in said hood to be engaged by said blade, the edges of one end of each of the two sections being spaced apart adjacent said shoulder over a portion of their length to provide an 70 aperture to receive said switch blade, and a closure member within said hood to close said aperture when the switch blade is out of the hood.
